DESIGN.

EX

J. ROGERS.
Statuary.

No. 7,960.

Patented Dec. 29, 1874.

David G. Francis
A. W. Warren

John Rogers

UNITED STATES PATENT OFFICE.

JOHN ROGERS, OF NEW YORK, N. Y.

DESIGN FOR STATUARY.

Specification forming part of Design No. **7,960**, dated December 29, 1874; application filed November 30, 1874
[Term of Patent 14 years.]

To all whom it may concern:

Be it known that I, JOHN ROGERS, of the city of New York, N. Y., have invented a Design for a Group of Statuary, of which the following is a specification:

The nature of my design is fully represented in the accompanying photographic illustrations.

The design is called "The tap on the window." The lover is startled by the noise, and turns his head toward the sound. He is seated on a chair, but still retains the left hand of the lady in his, though she tries to withdraw

it. She has risen from the piano-stool on which she has been sitting, and which she has partly overturned in so doing. She holds a fan to her face, a work-table is in front of her, and two kittens are playing around the lover's hat on the floor.

What I claim as my invention is—

A design for a piece of statuary, as above described.

JOHN ROGERS.

Witnesses:

DAVID G. FRANCIS,
N. W. WARREN.
